2,557,381

MULTIPLE UNIT PRINTING PRESS

William C. Huebner, New York, N. Y.

Application August 9, 1946, Serial No. 689,490

11 Claims. (Cl. 101—180)

1

This invention relates to a printing press and particularly to a press capable of printing or applying one or more colors to one or both sides of web material such as paper, film, textile, metal, cardboard or any other material capable of passing through the press.

The principal object of the invention is to provide a printing press which has a wide range of utility and can be readily set up for different printing runs to print various numbers of different colors on one or both sides of the print receiving material as desired.

Another object is to provide a printing press which is so constructed that one or more printing couples can be selectively incorporated into the press structure as desired, wherefore the printing press can be utilized for a variety of different printing purposes which heretofore would have required a number of presses and hence the press embodying the invention may be termed a "universal" press.

Another object is to provide a printing press wherein both sides of the print receiving material can be printed on simultaneously and one or more colors applied to said both sides as desired during a single run of the material through the press.

A further object is to provide a printing press which can be readily and quickly adapted for utilizing different printing methods or processes and can be quickly changed from a single color press to a multicolor press as desired.

A further object is to provide in a printing press means for mounting therein a system of cylinder carrying housings or units that can be readily moved into and out of printing relationship to provide easy accessibility to each and every cylinder and to facilitate the cleaning or the removal of each and every cylinder from the press.

Another object is to provide a printing press wherein series of printing units or elements constituting printing couples can be selectively mounted in a frame and which units or elements are relatively movable to each other to provide access to the print receiving material for various purposes as, for example, the purpose of reeling the material through the press initially or the purpose of repairing breaks in the material during the operation of the press.

A still further object is to provide a printing press comprising a frame in which a plurality of printing or inking elements or units can be mounted for adjustment relative to each other to provide accessibility and to render the press quickly changeable to different types of printing as well as for selectively printing one or more colors upon one or both sides of the web of print receiving material.

A further object is to provide a printing press which includes provision for drying by the use of heat and/or light the different printing colors intermediate the various printing stations and

2

which means can be readily moved to operative position or withdrawn from the press to an inoperative position for purposes of maintenance or for other reasons.

- 5 A further object is to provide a printing press for printing one or more colors on one or both sides of the web of print receiving material during a single run of the web through the press with the printing being performed either electrographically without pressure or in the more conventional ways involving the usual contact and pressure methods of printing and including the usual printing methods, i. e. direct or offset printing.
- 10 15 A still further object is to provide a printing press of the character hereinbefore referred to wherein, in addition to the adjustment of tiers of units relative to each other, provision is made for adjusting the cylinders or elements of cooperating units relative to each other to provide the desired clearance or pressure therebetween.

Further and additional objects and advantages not hereinbefore referred to will become apparent during the detailed description of the invention which is to follow.

Referring to the drawings,

Fig. 1 is a side elevational view of the press embodying the present invention with the press adapted for rotary printing a single color on both sides of the web of print receiving material during a single run of the web through the press by a single pair of printing units or couples, with the image carrying cylinders containing the ink which is expelled either by electro lines of force or by fluid pressure or both through the cylinder walls to the image areas on the exterior of the cylinder and then onto the print receiving material running in contact with the image cylinder.

40 Fig. 2 is a view similar to Fig. 1 but showing vertical series of five pairs of printing units or couples mounted in the press, wherefore five colors can be printed on both sides of the web of material during a single run of the web through the press.

45 Fig. 3 is a side elevational view of the press adapted for direct printing of five colors on each side of the web of print receiving material, with the image carrying cylinders of the press being inked by a roller system and being dampened by moisture expelled from the interior of the cylinders and with the right hand tier of inking units shown displaced longitudinally of the press from the right hand tier of image carrying cylinders, the printing being done either electronically without pressure or conventionally with pressure.

50 55 Fig. 4 is a side elevational view of the press adapted for printing five colors on both sides of the web of print receiving material during a single run of the web through the press, with the printing being done by offset printing cyl-

ders while the image carrying cylinders are inked by expulsion of the ink from the interior of the cylinders, either electronographically or by fluid pressure or both, with the right hand vertical tiers of image cylinders and ink carrying units moved to the right away from the tier of offset cylinders.

Fig. 5 is a view similar to Fig. 4, except that the image carrying cylinders are inked by inking rollers mounted in the ink carrying units and are dampened by moisture expelled from the interior of the image carrying cylinders.

Fig. 6 is an end elevational view of any of the presses shown in Figs. 1 to 5 inclusive.

Fig. 7 is a sectional view through the press and shows the gearing for shifting the movable vertical tiers of units longitudinally of the press.

Fig. 8 (sheet 7) is an end elevational view of the press showing the vertical bank of horizontally extending drying elements withdrawn from the press to provide accessibility to the cylinders and to the drying units.

Fig. 8a (sheet 8) is a plan view of the base of the press.

Fig. 9 (sheet 9) is a transverse vertical sectional view through a cylinder unit of the press.

Fig. 9a (sheet 8) is a fragmentary sectional view through a supporting member for a stationary tier of units.

Fig. 9b (sheet 9) is a fragmentary elevational view of the disk and drum of Fig. 9 and showing the key for correct positioning of the drum.

Fig. 10 (sheet 7) is an end elevational view on a reduced scale looking from the left hand end of Fig. 9.

Fig. 11 (sheet 7) is a sectional view on a reduced scale taken substantially on line 11-11 of Fig. 9.

Fig. 12 (sheet 10) is a sectional view on an enlarged scale and is taken substantially on line 12-12 of Fig. 3 looking in the direction of the arrows and shows the construction of an image carrying cylinder and its cooperating web support cylinder, with electronic discharge and attraction elements located in said cylinders, respectively, and means in the image cylinder for dampening the non-image areas of said cylinder.

Fig. 12a (sheet 8) is an elevational view of the inner side of either disk of the image cylinder shown in Fig. 12 and illustrates the grooves in said disks.

Fig. 12b (sheet 6) is an enlarged end view of a set of cooperating units forming a printing couple of the press shown in Fig. 3.

Fig. 13 (sheet 11) is a sectional view through an ink carrying unit such as is employed in the setup of the press shown in Figs. 1, 2 and 4, with the section taken substantially on irregular line 13-13 of Fig. 14 looking in the direction of the arrows.

Fig. 14 is an end elevational view of an ink carrying unit of a printing couple of Figs. 1, 2 and 4 and of its cooperating image carrying cylinder, with the rollers of the ink carrying unit out of contact with the image carrying cylinder and the ink being forced from the interior of the image carrying cylinder to the image areas electronographically or by fluid pressure or by both, the image carrying cylinder being of the type shown in Fig. 12.

Fig. 15 (sheet 13) is a wiring diagram showing a motor generator set common to a plurality of printing couples such as shown in Fig. 12b.

Fig. 16 (sheet 12) is a sectional view through

an ink roller unit such as shown in Figs. 3 and 5 with the section taken substantially on line 16-16 of Fig. 17.

Fig. 17 is an end elevational view of the ink roller unit shown in Fig. 16 and is taken looking from the left hand end of Fig. 16.

Fig. 18 is a view taken substantially on line 18-18 of Fig. 16 looking in the direction of the arrows.

Fig. 19 is a sectional view taken substantially on line 19-19 of Fig. 16 looking in the direction of the arrows.

Fig. 20 (sheet 11) is a view similar to Fig. 14 but showing a gravity feed for the ink between the ink carrying unit and the image carrying cylinder and also showing the web of print receiving material passing around the image carrying cylinder with the clean supporting rollers of the ink carrying unit in contact with said web, i. e., the arrangement shown in Figs. 1 and 2.

Fig. 21 (sheet 13) is a sectional view taken substantially on line 21-21 of Fig. 20 looking in the direction of the arrows, and

Fig. 22 is a fragmentary sectional view taken substantially on line 22-22 of Fig. 21 looking in the direction of the arrows.

The present invention contemplates a universal press which is so constructed that different types and different numbers of printing units and inking or ink carrying units can be selectively employed in a standardized frame, with the units of one type adjustable longitudinally of the frame relative to the units of the other type to provide accessibility for setup, maintenance and operative purposes. In this way the press may be adapted readily and quickly for pressure printing or electronographic printing without pressure either by direct or offset printing processes, and, in addition, the press can be quickly adapted for printing one or more colors on one or both sides of the web of print receiving material during a single run of the web through the press. In view of the varied utility of the press it may well be designated as a universal press since the single press can perform a wide variety of different types of printing with a plurality of colors as desired on one of both sides of the web of print receiving material and thus replaces a number of conventional presses which would be required to cover the same range of utility.

A universal press embodying the present invention would consist of the standardized frame and sets of standardized printing units of various types and standardized inking or ink and liquid carrying units which could be selectively assembled in the frame as desired and as will be pointed out hereinafter.

The frame of the press comprises a base 30 which is of generally rectangular configuration (see Fig. 8a). The base 30 on its upper side and adjacent to its opposite ends is provided with machined surfaces 31 located adjacent to the front and rear longitudinal edges of the base and acting as supports for four uprights 32 which are provided at their lower ends with flanged foot portions 33 bolted or otherwise rigidly secured to the machined surfaces 31, see Fig. 6. The base 30 on its upper side is also provided adjacent its front and rear edges with longitudinally extending parallel rails 34 which preferably terminate near the middle point of the base to provide a gap in each rail for a purpose later to be explained. The rails 34 may be formed integral with the base or they may be attached thereto as shown in Fig. 8a. The lower ends of the uprights 32 are pro-

vided with recesses which interfit the rails 34 so that the rails act as keys to locate the uprights and stabilize the same in their vertical positions and thus lend rigidity to the frame as well as facilitating the assembly of the frame members (see Fig. 6).

The frame includes a top or cover structural member 35 which is rigidly secured by bolts or other suitable means to the upper ends of the uprights 32 to form with said uprights and the base a rigid frame structure. The cover member 35 is provided in its underside with longitudinally extending grooves 36 aligned with and parallel to the rails 34 of the base member for a purpose later to be explained. The frame of the press just described may be so dimensioned as to accommodate vertical tiers of three units each, for example where the maximum number of colors that are to be printed by the press is known to be three, see Fig. 1, or the frame may be so dimensioned as to accommodate a different number of units in the vertical tiers of units, as for example, five units in each vertical tier as shown in Fig. 2 or to accommodate a still greater number if desired. In most instances the frame of the press would be as shown in Fig. 2, so that the press would have a maximum color capacity of five colors to cover the usual number of colors required in multicolor printing. However, seven color printing consisting, for instance, of red, yellow, blue, green, purple, white and black might be desired, and it will be understood that then the frame would be dimensioned to accommodate seven units in the vertical tiers.

It will be noted that the base 30 and the cover member 35 can be standardized for presses capable of printing any number of different colors, while the uprights 32 can be manufactured in sets of such length as required for printing three, five, seven or any other number of colors and can be assembled into the frame structure with the base 30 and the cover member 35 as desired by a customer.

Intermediate the uprights 32 and mounted on the ends of the rails 34 adjacent the intermediate gaps in said rails at the front and rear of the base are a pair of stationary tier supporting members 37 which are provided in their undersides with recesses interfitting the rails 34 and bolted rigidly to the base, see Fig. 9a. The upper surface of each member 37 is provided with a longitudinally extending key 38. A plurality of identical drum housing units 39, see Fig. 9, is mounted on the supporting members 37 intermediate said members and the cover 35. In Fig. 1 two stationary vertical tiers of three such units are shown, while in Figs. 2, 3, 4 and 5 the two stationary vertical tiers of these units include, for purposes of illustration, five units each. Each unit 39 extends transversely of the base and is provided on its underside with keyways 40 and on its upper side with keys 41 (see Fig. 9). The keyways 40 of the lowermost unit 39 of each stationary vertical tier of units interfit the keys 38 of the supporting members 37. The keys 41 of the top unit 39 of each stationary vertical tier of units interfit the grooves 36 in the cover member 35 while intermediate the supporting members 37 and the cover member 35 the adjacent keys 41 and keyways 40 of the units 39 interfit each other. The units 39 are rigidly connected together and to the supporting members 37 and the cover 35 by suitable securing means such as the bolts 42 shown in Figs. 9 and 9a. It will thus be seen that the vertical stationary tiers of the units 39

in effect constitute rigid vertical frame members intermediate the uprights 32. Each stationary tier of drum or cylinder housing units 39 will hereinafter be designated in its entirety as tier A.

- 5 In addition to the stationary tiers A the press will contain adjustable vertical tiers of cylinders or roller supporting units, similar to the units 39 and adjustable vertical tiers of inking or ink and liquid carrying units which later will be described.
- 10 The ink or ink and liquid carrying units 43a are shown in Figs. 1 and 2 as adjacent to the units 39, while in Figs. 3, 4 and 5 the ink or ink and liquid carrying units 43 and 43a are shown 15 as separated from the units 39 by adjustable vertical tiers of cylinder supporting units. The longitudinally adjustable vertical tiers of units 43 or 43a will hereinafter be referred to in their entirety as tiers of units B. The tiers of units 20 43 or 43a and the adjustable tiers of cylinder supporting units are secured to movable supporting members 44 similar to the supporting members 37 for the stationary tiers A except that said members 44 are provided on their undersides with longitudinally extending grooves in 25 which are mounted rollers 45 that ride on the rails 34. The units of the movable tiers are secured to the members 44 and to each other, with the key 41 of the uppermost unit of each 30 tier extending into and movable in the grooves 36 of the cover 35. Therefore each movable vertical tier of units can move longitudinally of the frame of the press for purposes later to be explained.
- 35 Referring to Fig. 3 it will be noted that intermediate the stationary tiers A and the adjustable tiers B are longitudinally adjustable vertical tiers of drum or cylinder housing or supporting units 39, the lowermost of which are secured to movable supporting members 44 while the uppermost of which have their keys 41 slidably guided by the grooves 36 of the cover member 35 as already described. The adjustable vertical tiers of units 39 shown in Fig. 3 will be designated hereinafter in their entireties as tiers C.
- 40 In Figs. 4 and 5 second adjustable vertical tiers of units 39 are located intermediate tiers A and C and said second adjustable tiers will hereinafter be designated in their entirety as 45 tiers D.
- 50 A shaft 46 is rotatably supported by each pair of supporting members 44 of each adjustable tier B, C or D, while the uppermost units of each of said adjustable vertical tiers rotatably support shafts 47 (see Fig. 7). The shafts 46 and 55 47 have fixed thereto pinions 48 which mesh with elongated racks 49 carried by the upper side of the base 30 and the underside of the cover 35 and extending parallel to the rails 34, wherefore it will be seen that when the shafts 46 and 47 are rotated with an equalized rotation the adjustable vertical tiers B, C and D can be moved longitudinally of the frame without deflecting the tiers from a true vertical position.
- 60 65 The shafts 46 have one end thereof extended beyond the rear side of the press and such extended end is provided with a bevel gear 50 fixed to the shaft while a crank handle 51 may be applied to a portion of the shaft at the front side of the press. Certain of the units 39 of the tiers C and D and certain of the units 43 or 43a of the tiers B are provided with brackets 52 which 70 rotatably mount vertically extending shafts 53 carrying at their lower ends bevel gears 54 meshing with the bevel gears 50 on the shafts 46 and 75 55

at their upper ends bevel gears 55 meshing with bevel gears 56 on the shafts 41. In this way each tier B, C and D can be longitudinally moved in the frame relative to the other tiers B, C and D and to the stationary tiers A.

In Figs. 1 and 2 adjustable tiers B are shown as located closely adjacent to stationary tiers A and in the positions they occupy during the operation of the press.

In Fig. 3 the tiers C are closely adjacent and in operative position with respect to the stationary tiers A, while the left hand tier B is closely adjacent to and in operative position with respect to the left hand tier C. However, the right hand tier B is shown as having been moved away from the right hand tier C and adjacent to the right hand upright 32 for a purpose later to be explained.

In Figs. 4 and 5 the left hand tiers A, B, C and D are shown as located closely adjacent to each other and in operative relationship, while the right hand tiers B and C are shown as moved toward the right and spaced from the right hand tier D for a purpose later to be explained.

In order to secure the adjustable tiers B, C and D in adjusted operative position the supporting members 44 and the uppermost unit of each tier may be locked to the base 30 and the cover 35 by any suitable means as, for example, by means of tapered dowel pins 57 insertable through aligned openings in the supporting members 44 and the uppermost units and the base 30 and cover 35, see Fig. 9.

In Figs. 1 and 2 the press is shown as adapted for simultaneously printing on both sides of the web of print receiving material during a single run of the material through the press. In Fig. 1 a single color is printed on both sides of the web of material while in Fig. 2 five colors may be printed on both sides of the web of material.

Referring to Figs. 1 to 5 inclusive, the lowermost unit 39 of each tier A, C and D mounts a drum or cylinder of a selected type and later to be described in detail. Each unit 39 comprises rotatable spaced apart drum supporting disks 59 and 60 (see Fig. 9). The disk 59 is rotatably supported for adjustment in an eccentric bushing 61 that can be locked in various adjusted positions. The bushing 61 is mounted in an eccentric sleeve 62 which carries a key 63 that extends into a keyway 64 in the bushing, wherefore the bushing together with the bearing for the disk 59 which rotates in the bushing can have endwise movement relative to the sleeve. The bushing 61 is externally threaded and supports a gear nut 65 located between the flange of the sleeve 62 and a retainer plate 66 rigidly secured to said flange. A pinion 67 meshes with the teeth of the nut 65 and is fixed to a shaft 68 that is rotatably supported by the flange of the sleeve and by the plate 66 and has its outer end formed with a portion to which a removable operating handle 69 can be attached. It will thus be seen that when the pinion 67 is rotated by the handle 69 the nut 65 will be turned to cause the bushing 61 to slide axially inwardly or outwardly, depending upon the direction of rotation of the handle 69.

The disk 60 has its bearing mounted in an eccentric bearing sleeve 70 but said bearing of the disk is held against axial displacement. A sleeve 71 is fixed to a reduced portion of the bearing of the disk 60 between the bearing and the eccentric bearing sleeve 70 and is provided with a shoulder engaging the outer side of the bearing sleeve.

The sleeve 71 has formed thereon a gear 72 which will later be referred to. Each disk 59 and 60 on its inner face has secured to it a supporting plate 73 which is provided at its circumference with a circular shoulder mounting in some instances a spacing ring 74. The supporting plates 73 are adapted to support various types of drums or cylinders which have their opposite ends bearing upon the rings 74 or upon the circular shoulders of the plates 73 as the case may be when the disks 59 and 60 are positioned apart at the proper distance.

The disk 59 is provided centrally with a recess facing toward the disk 60 and mounting a bearing 75 adapted to support a stationary tube 76 which extends through central openings in the plates 73 with a substantial clearance being provided between the tube and the plates. The tube 76 extends slightly into a central bore in the disk 60 and is detachably connected by a tongue and groove connection with a fixed tube 77 stationarily mounted in the bore of the rotatable disk 60 and extending through the bearing thereof and into a supporting boss formed in the wall of the unit 39.

Assuming that the disks 59 and 60 are positioned in drum supporting relationship and that a drum or cylinder is mounted on the circular shoulders of the plates 73 or on the rings 74, and also assuming that the tube 76 is in position as shown in Fig. 9 and is connected to the tube 77, it will be seen that rotation of the disk 60 will cause the drum or cylinder and the disk 59 to rotate while the tubes 76 and 77 are stationary. Now assuming that it is desired to remove the cylinder or drum, the operator applies the handle 69 to the outer end of the shaft 68 and rotates said shaft to cause the bushing 61 and the disk 59 to move outwardly as has been previously explained and away from the disk 60, with the result that the circular shoulders on the plates 73 are spaced apart a greater distance than the length of the cylinder or drum, it being understood that the disk 59 can move outwardly until it contacts the wall of the unit 39. The outward movement of the disk 59 also causes separation of the left hand end of the tube 76 from the bearing 75, thus both the drum and the tube 76 will be freed for removal from the unit. When it is desired to insert a drum or cylinder in the unit as for instance, another type of drum or cylinder, the drum or cylinder with the tube 76 therein is inserted into the unit with the right hand end of the drum, as viewed in Fig. 9 resting upon the shoulder of the right hand plate 73 or upon the ring 74 and with a rod passing through a central opening 78 in the disk 59 holding the tube 76 in properly aligned position with the tube 77 and with the bearing 75 of the disk 59. The cylinder or drum which may be of plain metal type as shown in Fig. 9 is positioned so that a notch 79 in its right hand end aligns with and receives a key 80 carried by the disk 60. The operator then turns the handle 69 to cause the disk 59 to move inwardly toward the disk 60 until the cylinder or drum is tightly clamped on the circular shoulders of the plates 73 or the rings 74 and the left hand end of the tube 76 is in the bearing 75. The structure above described relating to the relative movement of the disks 59 and 60 to clamp the cylinder or drum therebetween or to spread the same to enable the cylinder or drum to be removed is claimed in my divisional application, Serial No. 109,306, filed August 9, 1949. An alternative way of mounting a drum or cylinder in

position is to remove the plates 73 and assemble the cylinder on the shoulders of the plates and then insert the tube 76 through the central openings of the plates. This assembly can then be mounted at one end on the disk 60 while its other end is supported by a tool in the opening 78 and having a squared end engaging the square socket in the end of the tube 76. The tube 76 is thus centered and can be rotated to engage the tongue and groove connection between it and the tube 77. The disk 59 can then be moved into supporting relationship with its cooperating plate 73.

It will be recalled that the bearing for the disk 59 is supported in a bushing which in turn is supported in the adjustable sleeve 62 while the bearing for the disk 60 is supported in the adjustable eccentric sleeve 70. Therefore said sleeves 62 and 70 can be rotated to shift the axes of the disks and the axis of the cylinder or drum carried by the disks to adjust slightly the cylinder or drum of a unit of one tier relative to the cylinder or drum of the unit of another tier to provide the desired contact pressure or spacing between the cylinders or drums.

After the disks have been adjusted the eccentric sleeves are clamped in adjusted position by means of suitable clamping screws 62a and 70a. In connection with the adjustment of the axes of the disks 59 and 60 it will be understood that clearance exists between the disk 60 and its bearing and the fixed tube 77 so that the shifting of the disk 60 and its attached gear 72 can take place with a slight misalignment of the stationary tube 77.

The gear 72 of each unit is driven in the manner now to be explained. A motor base 81 extends laterally from one longitudinal side of the main base 3 and adjacent an end thereof, see Figs. 8 and 8a, and supports a motor 82 which drives a shaft 83 by any suitable operative connection such as a pulley and belt connection. The shaft 83 extends longitudinally of the frame and passes through a housing and gear guard 84 of the units 39 or 43 or 43a of each vertical tier of units. The shaft 83 is rotatably mounted in suitable brackets carried by the frame of the press but is held against endwise movement. Within the housing portion of the housing and gear guard 84 a spiral gear pinion 85 is splined to the shaft 83 to rotate therewith and move endwise thereof, wherefore each tier of units can be adjusted longitudinally of the frame. The cylinders or drums of the tiers A, C, and D are driven from the shaft 83, as indicated in Fig. 9, wherein a spiral gear 86 in mesh with the pinion 85 is fixed to a shaft 87 that is rotatably supported in the housing portion 84 and in the lowermost unit. The shaft 87 has fixed to its inner end a gear 88 which meshes with the gear 72 previously referred to. The gear 72 of the unit 39 above the lowermost unit 39 is driven from the gear 72 of said lowermost unit by means of an idler gear 89 which is mounted on a flanged bearing shaft 90 which can be adjusted and clamped in adjusted position by a screw or screws 91 which extend through openings in the flange of the shaft of larger diameter than the screws, wherefore the gear 89 can be adjusted in any direction. This provides for maintaining the proper intermeshing relation between the gears 88 and the gears 72 when the axes of the drums or cylinders on one tier are adjusted relative to the axes of the drums or cylinders of another tier as previously explained. It will be understood that the gears 72 of all the units 39 in each tier are driven from the gear 72 of the lower-

most unit by means of adjustably interposed idler gears 89.

The cylinders or drums of the units 39 may take various forms as will presently become apparent.

Fig. 12 is a sectional view through a cylinder of tier A and a cooperating cylinder of tier C of Fig. 3. The cylinders of tier A are, in this instance, simply web supporting cylinders and comprise suitable metal or other cylinders 92 carried by the plates 73 as described in connection with Fig. 9. The cylinders or drums 93 of tier C are formed of any suitable porous material through which moisture can pass.

In Fig. 3 the cylinders 93 are provided on their exteriors with image portions that are impervious to the passage of moisture therethrough and with non-image portions that are pervious to the passage of moisture. In this arrangement the cylinders 93 have their image areas inked by inking rollers carried by the units 43 of tier B. In addition, the non-image areas of the cylinders 93 are moistened or dampened by means of water or other liquid that is expelled from the interior of the cylinders through the pores thereof thus making said non-image areas ink repellent. Reference to Fig. 12 will show that the cylinder 93 surrounds a cylinder 94 and is slightly spaced therefrom with both cylinders supported on the circular shoulders of the plates 73. The cylinder 94 is provided with a plurality of parallel spiral grooves 95 each of which connects with a radial groove formed in the inner faces of the disks 59 and 60 and connecting in turn with radial grooves 96 formed in said disks (see Fig. 12a) and extending to a circular passageway in communication with the interior of the stationary tube 76 on one side of the partition 97 that divides said tube into two compartments. The compartment 35 in the tube 76 just referred to is connected to a pipe 98 which in turn is connected to a flexible hose 99, see Fig. 12b that extends to a tank 100 mounted in the adjacent unit 43 of tier B, it being understood that the hose 99 is of sufficient length to allow for maximum separation of the tiers B and C.

In the instance shown in Fig. 12b the tank 100 is under fluid pressure and preferably the tank carries a gauge 101 to indicate such pressure. The liquid in the tank 100 is thus forced from the tank through the hose 99, pipe 98 and into the compartment of the tube 76 and thence to the spiral grooves 95. The connection between the liquid compartment of the tube 76 and the pipe 98 is by means of a detachable coupling 50 which can be quickly disconnected or connected when the tube is removed from the cylinder or is mounted in the cylinder. It will be seen that rotation of the cylinder 93 when the liquid is in the spiral grooves 95 under pressure will cause 55 the liquid to work along the entire longitudinal length of the circumference of the cylinder 94 and such that it will moisten or dampen the entire inner surface of the drum 93 and will pass through the pores of the drum in the pervious non-image areas to dampen said non-image areas so that said areas will not be inked by the inking rolls 102 of the units 43 of the tier B.

In the example shown in Figs. 3 and 12 it is proposed to transfer the ink from the inked image areas of the cylinder 93 to the web W of print receiving material passing between the cylinders 92 and 93 by means of electrostatic lines of force and without pressure as clearly explained in my prior Patent No. 2,224,391, issued December 10, 70 1940.

The tubes 76 in the cylinders 92 and 93 carry rubber insulating tubes 103 and the supports 104 for the discharge element 105 and the attraction element 106 are clamped about the rubber tubes 103. The discharge element is located within the cylinder 94 while the attraction element is located within the cylinder 92 and said elements extend substantially the longitudinal length of the cylinders and have their free edges adjacent the inner circumference of the cylinders. The element 105 is connected to an electric lead 107 which extends through the compartment of the tube 76 that is separated from the liquid compartment by the partition 97 and is connected by a detachable electric coupling to a lead 108 in the tube 77. The lead 108 is connected by a flexible cable 109 to a rheostat 110 which in turn is electrically connected to one terminal of a motor generator unit 111, said rheostat and said motor generator unit being carried by the adjacent unit 43 of tier B. The element 106 in cylinder 92 is connected to an electrical lead 112 which extends through the tube 76 and is electrically connected by means of a detachable coupling with a lead 113 which in turn is connected by a flexible lead 114 to the other terminal of the motor generator unit 111. It will be seen that when the motor generator unit is operating, high potential current will be supplied to the electric circuit including the elements 105 and 106, with the result that electrostatic lines of force will bridge the gap between the adjacent free edges of said elements passing through the cylinders 94, 93 and 92 and acting to carry the ink on the image areas of the cylinder 93 from said areas to the web of print receiving material to thus reproduce the image on said material.

As already stated, each unit 43 mounts inking rolls 102 which are in contact with driving rollers 115 (see Fig. 19). The rollers 115 are mounted by the unit 43 for rotation and also for axial reciprocation so that the ink will be uniformly distributed on the inking rolls 102. The driving rolls 115 are driven in the following manner:

The shaft 83 which extends through the housing 84 of the lowermost units of the tiers of units carries a spiral gear 116 within the housing 84 of the lowermost unit 43 and said gear meshes with a spiral gear 117 formed on a sleeve rotatably mounted in the housing 84 and which sleeve also carries a gear 118 which meshes with an elongated pinion 119 fixed to a rotatable shaft 120 that is mounted in the end walls of the unit 43 intermediate the axes of the rolls 115. The shaft 120 on its end opposite to that which carries the pinion 119 has fixed thereto a cam 121 later to be referred to. The rolls 115 are carried by shafts 122 rotatably mounted in the end walls of the unit 43 and projecting outwardly of said rolls. The shafts 122 have fixed thereto gears 123 which mesh with the elongated pinion 119, wherefore the shafts 122 and rolls 115 are rotatably driven from the shaft 83. The shafts 122 on their opposite ends have fixed thereto follower disks 124 which engage in the cam groove of the cam 121 and hence it will be seen that said cam 121 as it rotates will act through the followers 124 to oscillate axially the shafts 122 and rollers 115. The driving rollers 115 are also in contact with idler rolls 125, which latter rolls in turn contact a smaller driving roll 126 mounted on a shaft 127 that can rotate and axially reciprocate and carries on one end a gear 128 meshing with the pinion 119 and on its opposite end a follower disk 129 that rides in the cam groove of the cam 121. The smaller driving roll 126 runs in contact with

an idler roll 130 which in turn runs in contact with the circumference of a reservoir drum 131 constructed of porous material. The drum 131 includes end members 132 which are rotatable on a fixed hollow shaft 133, suitable packing 134 being interposed between the end members 132 and the shaft 133. The shaft 133 is held against axial shifting in the walls of the unit 43 by means of collars 135 fixed to the shaft and engaging the inner sides of the walls of the unit. The hollow shaft 133 is provided with a plurality of openings 136 and the interior of said shaft is connected to a suitable ink supply source by a conduit 137. It will be seen that ink flowing from the hollow shaft 133 and into the drum 131 will pass through the pores of said drum and onto the idler roll 130 from whence it will go to the reciprocating driving roll 126 to the idler rolls 125 to the reciprocating driving rolls 115 and thence to the inking rolls 102 from where it will be transmitted to the image portions of the image cylinder 92. It will be understood that the ink supplied to the hollow shaft 133 is under pressure to facilitate the flow of ink and the passage of the same through the pores of the drum 131 and a suitable pressure gauge 137a can be provided to indicate to the operator the pressure that is acting on the ink. All of the units 43 in the tiers B will be equipped with similar inking rolls and said rolls will be driven by means of a gear 138 which meshes with the pinion 119 and drives in turn a gear 139 that extends beyond the upper edge of the lowermost unit 43 and is in mesh with a gear similar to the gear 118 carried by the next unit. In this way all of the inking rolls and driving rolls of the units 43 of the tiers B can be driven from the shaft 83.

Reference should now be made to Figs. 1, 2, 13 and 14. In Figs. 1 and 2 the ink is expelled from 40 interiorly of the cylinder or cylinders in tier A and is transferred from the image areas of the cylinder to the web of print receiving material which runs in contact with the cylinder. In this arrangement the cylinder or cylinders in tiers A are similar in construction to the cylinder 93 of Fig. 12 previously described, except that the cylinder or cylinders of Figs. 1 and 2 are provided with image areas that are pervious to the ink and non-image areas which are impervious thereto, it being recalled that the reverse arrangement is used in the cylinder 93 of Fig. 12 for the purpose of dampening the non-image areas of the cylinder. The cylinder or cylinders of tiers A of Figs. 1 and 2 have been designated previously herein with the numeral 58 but it will be understood that said cylinders are similar to the cylinders 93 of tiers C of Fig. 3 as already explained.

Referring to Fig. 14, it will be noted that the liquid compartment of the fixed tube 76 of each cylinder 58 is connected by a flexible hose 140 to a fixed ink tank or reservoir 141 mounted in the adjacent unit 43a, see Figs. 13 and 14. The tank or reservoir 141 is subject to fluid pressure and is provided with a suitable pressure gauge 141a, wherefore the ink will be forced from the tank or reservoir at a predetermined pressure through the hose 140 and into the spiral grooves 95 of the cylinder 58 in the same manner as the moisture was forced into said grooves in cylinder 93, as previously explained. The unit 43a is provided with a motor generator unit 111, as previously explained, with one terminal thereof connected to a rheostat 110 which in turn is electrically connected by a flexible lead 142 to an electrostatic discharge element 143 located within the cylinder

58. The other terminal of the motor generator unit 111 is connected by a lead 144 to an electrostatic element 145 carried by the unit 43a and aligned with the element 143 with said elements located on opposite sides of the web W which passes around the cylinder 58. It will be seen that the ink in the spiral grooves 95 of the cylinder 58 will be dispersed over the interior of the porous cylinder and said ink will be carried by the electrostatic lines of force between the elements 143 and 145 through the pores of the image areas of the cylinder 58 and onto the web W of print receiving material to reproduce thereon the desired image.

In the unit 43a the support for the element 145 is on a fixed bar 146 mounted in the unit in place of the shaft 120 of the unit 43 of Figs. 16 to 18 inclusive.

Figs. 20, 21 and 22 show an arrangement similar to that shown in Fig. 14 except that a somewhat different arrangement for inking the image areas of the cylinder 58 is illustrated. In Figs. 20, 21 and 22 the tube 76 is connected to the ink reservoir 141 in the same manner as in Fig. 14 except that the reservoir 141 is not subject to fluid pressure.

In Figs. 20 to 22 inclusive the interior of the ink compartment of the tube 76 of the cylinder 58 is connected by a plurality of pipes 147 with an open ink containing trough 148 mounted on suitable supports carried by the tube 76. It will be seen that the ink in the reservoir 141 will flow by gravity into the trough 148 until the level of the ink in the trough corresponds to the level of the ink in the reservoir. The tube 76 also carries standards 149 which at their free ends rotatably support a shaft 150 which carries an ink roller 151 that rolls in contact with the interior of the cylinder 58. Hence it will be noted that in this form the use of the inner cylinder 94 within the cylinder 58 is dispensed with and also the employment of the spiral grooves 95 is likewise not required, it being understood that the roller 151 rotating in the ink applies the ink to the interior of the cylinder 58 to be carried by the electrostatic lines of force through the porous image areas of the cylinder.

It will further be understood that a like arrangement could be employed in connection with the arrangement shown in Fig. 12 for the purpose of dampening the interior of the cylinder 93 so as to have the moisture carried through the porous non-image areas of the cylinder. The image areas will be dry and hence compatible to receiving the ink while the non-image areas being moistened are ink repellent.

In the arrangement shown in Fig. 4 the cylinders of tiers C are image cylinders similar to the cylinders 58 of Figs. 14 and 20 and in such an arrangement the ink can be expelled from interiorly of the cylinders to the surface thereof through the previous image portions by electrostatic lines of force as previously described, it being preferable in this latter instance to employ a current of low voltage for producing the electrostatic field of force since the ink merely has to be brought to the exterior surface of the cylinders. It will be understood that the inked image areas of the cylinders of tiers C of Fig. 4 then reproduce the image to be printed on the rubber blanket or offset cylinders of tiers D which latter in turn print the image on the web W which extends around the cylinders on the supporting tiers A. It will also be understood that the rollers 102 in Fig. 20 are spaced from the drum 58 and that the web

W in both Figs. 14 and 20 does not surround the image drum 58 in tiers C of Fig. 4.

Heretofore each unit 43 or 43a has been described as equipped individually with a motor generator unit. It will be understood that an arrangement can be employed if desired wherein a single motor generator unit will function for more than one unit 43 or 43a and such single motor generator unit may be of larger capacity than the individual motor generator units and can be located in a suitable position behind the machine.

In Fig. 15 there is diagrammatically illustrated an arrangement for a single motor generator unit which provides the current for a plurality of electrostatic fields of force. This motor generator unit is indicated at 152 and one terminal thereof is connected by a common lead 153 to a plurality of branch leads 154 each extending to a rheostat 155. Each rheostat 155 is electrically connected in turn to a discharge element 156. The other terminal of the motor generator unit 152 is connected to a common lead 157 which in turn is connected to a plurality of branch leads 158, each of which extends to an electrostatic attraction element 159. It will thus be seen that the motor generator unit 152 provides current for a plurality of sets of electrostatic discharge and attraction elements and the current for each set of elements can be individually regulated by its respective rheostat 155.

Reference has been made to the arrangement shown in Fig. 4 wherein the ink is expelled from interiorly of the image cylinders of tiers C to the image areas thereof and units 43a are employed in conjunction with said image cylinders.

Referring to Fig. 5, it will be noted that the image cylinders of tiers C are inked by the inking rolls of the units 43, as previously explained, in connection with the inking of cylinders 92 in Figs. 16 to 19 inclusive, or the inking of cylinders 93 of tiers C as explained in reference to Fig. 12b. In the latter instance it will be recalled that the non-image areas of cylinders 93 are dampened by the expulsion of moisture from within the cylinders as explained in connection with Fig. 12 and Fig. 12b.

In Fig. 5 the image cylinders of tiers C impress the inked images on the rubber blanket or offset cylinders of tiers D and the latter in turn print the images on the web W carried by the supporting cylinders of tiers A as explained in connection with Fig. 4.

Referring to Fig. 8a, it will be seen that the base 30 intermediate its ends and on one side thereof has secured to it a laterally extending base portion 160. The base portion 160 has secured to its upper side parallel rails 161 which extend over the base 30 and are secured thereto intermediate the gaps in the rails 34 of the base 30.

Referring to Figs. 8 and 8a the rails 161 of the base portion 160 support the horizontal leg 162 of a substantially L-shaped supporting member 163, suitable rollers 164 being interposed between the rails 161 and the underside of the leg 162 of said supporting member to facilitate the movement of the member along the rails. The supporting member 163 is provided with a plurality of vertically spaced parallel inclined heating and/or light element supports 165 mounting one or more heating or drying elements 166 which may take various forms but are indicated herein as constituting elongated tubular heating or lighting elements (see Figs 1 to 5). The elements 166 can be connected to any suitable source of heat or

light producing energy as, for example, electrical energy. It will be seen that when the support 163 is moved inwardly or toward the left as viewed in Fig. 8 the element supports 165 are located intermediate the lengths of the web W of print receiving material which is reeved around the cylinders of tiers A and thus the heat or light produced by the elements 166 is effective on both sides of each length of the web W to quickly dry or fix the ink which has been applied thereto. It will also be noted that the support 163 can be moved outwardly to the position shown in Fig. 8 to provide access to the space between the cylinders of tiers A in order to enable the operator to reach the web W of print receiving material in setting the press up for operation or in repairing the web in case of a break therein.

In order that the description hereinbefore set forth may be coordinated and emphasis placed on the different setups of the press which can be made to enable it to function as a universal press capable of printing by various types of printing one or more colors on one or both sides of a web of print receiving material during a single run of the web through the press reference will now be made to the different arrangements shown in Figs. 1 to 5 inclusive.

In Fig. 1 the press is set up to print a single color on both sides of the web W of print receiving material during a single run of the web through the press. The fixed tiers A are arranged to have in the lowermost units 39 thereof cylinders 58, as described in connection with Figs. 14 or 20 and wherein the ink is expelled from interiorly of the cylinders 58 to the image areas thereof. In this arrangement a tier of units 43a is employed in each tier B with the clean rolls corresponding to the inking rolls 102 of the units 43 acting simply as contact rolls if desired to hold the web W against the cylinders 58. The web W of print receiving material is fed from a supply roll 167 and passes in the direction indicated by the arrows over a plurality of idler rolls 168 located adjacent to the base 30 near one end thereof and then passes upwardly of the left hand uprights 32 as viewed in Fig. 1 over a guide roller 169 supported in the cover and thence to a guide roller 170 also supported in the cover and located intermediate the ends of the cover 35. From the guide roller 170 the web passes down and around the right hand cylinder 58 and thence around the left hand cylinder 58 from which it passes in contact with a guide roller 171 in the right hand tier supporting member 37 and around a plurality of guide rolls 172 located adjacent the right hand uprights 32 and thence to a winding roll 173. The supply roll 167, winding roll 173 and guide rolls 168 and 172 are carried by suitable supporting members mounted on the base 30 and the supply roll 167 and winding roll 173 may both be driven in timed relation with the movement of the web by any suitable driving means well known in the art. The ink is expelled from interiorly of the cylinders 58 to the image areas thereof and from said areas is deposited onto the surfaces of the web W of print receiving material. It will be noted that the web W is in contact with the printing surfaces of the cylinders 58 for approximately half of the circumference of said cylinders and thus there is provided the desired time element for permitting the needed and proper amount of the ink to be deposited on the surfaces of the web so that a desired heavy ink deposit may be obtained as distinguished from orthodox printing where the web has only a line contact to receive the ink impression.

The press frame shown in Fig. 1 is so dimensioned that the tiers A and B can each accommodate three units to enable the press to print on both sides of the web three different colors during a single passage of the web through the press.

In Fig. 2 the press is illustrated with an arrangement similar to Fig. 1 except that the press frame is dimensioned to enable a maximum of five units to be mounted in each of the tiers A and B of the press to enable the press to print a maximum of five colors on each side of the web during a single passage of the web through the press.

Reference should now be made to Fig. 3 it being noted first that the right hand tier B of units 43 is shown as moved longitudinally of the frame toward the right in spaced relation to the units of tier C. In this case it will be understood that either of tiers B of the presses shown in Figs. 1 and 2 can be similarly moved away from its operating tier A for the purpose of setting up the press, reeving the web therein, removing or cleaning the cylinders or for other setup or maintenance purposes.

The press shown in Fig. 3 has the cylinders of tiers A arranged to act as web supporting cylinders. This press includes tiers C of image cylinders 93 located intermediate the tiers A and B. In the press of Fig. 3 the image cylinders 93 have their image areas inked by inking rolls of the units 43, while the non-image areas only are damped in the manner previously explained in connection with Fig. 12.

The inked image areas of the cylinders 93 of the two tiers C print the images on both sides of the web W during a single passage of the web through the press either electronographically without pressure or by contact with pressure as desired, and it will be noted that the press of Fig. 3 is set up to print a maximum of five colors on both sides of the web.

In Fig. 4 the press is set up with tiers D of rubber blanket or offset cylinders located intermediate the web supporting cylinders of tiers A and the image cylinders of tiers C. In this arrangement the ink is carried from the units 43a of tiers B to the interior of the image cylinders of tiers C and is expelled through the porous image areas thereof to the exterior of said cylinders, in order to ink said image areas. The inked image areas of the cylinders of tiers C then reproduce the image on the offset cylinders of tiers D and the latter cylinders in turn reproduce by the offset method the images on both sides of the web W of print receiving material. It will be noted that the contact rolls of the units 43a of tiers B are slightly out of contact with the image cylinders of tiers C. The ink from within the image cylinders of tiers C can be expelled to the image areas thereof either as described in connection with Fig. 14 or Fig. 20.

It will be noted that the web W of print receiving material is shown as passing through the press in the reverse direction from that shown in Figs. 1 to 3 inclusive and this arrangement is an optional one which can be used if desired, particularly if the web is to be fed into cutting, folding and collating equipment. It will also be noted that the right hand tiers B and C are shown spaced from the right hand tier D, thus illustrating the manner in which the movable tiers can be moved to afford the operator access to the cylinders and other parts of the press as desired.

The arrangement of the press shown in Fig. 5 is

similar to that shown in Fig. 4 except that here the tiers B are formed of the units 43 and the image cylinders of tiers C are inked by the inking rollers, it being recalled that the non-image areas of the image cylinders can be damped by moisture expelled from within the cylinders. It will also be noted that in Fig. 5 the web travels through the press in the same direction as in Figs. 1 to 3 inclusive.

From the foregoing review of the press setups shown in Figs. 1 to 5 inclusive it will readily be appreciated that the universal press constructed in accordance with the present invention can quickly and easily be adapted for printing one or more colors on both sides of the web during a single run of the web through the press and that the printing can be performed by different types of printing as desired, thus indicating the wide range of utility possessed by the press. In this connection it will readily be understood that the universal press embodying the present invention can supplement a plurality of conventional single purpose presses and can be adapted as desired to perform all the functions of all of said conventional single purpose presses. In addition the universal press involves a radical departure over the conventional presses in that it can print one or more colors simultaneously on both sides of the web during a single passage of the web through the press.

It will also be noted due to the use of the movable tiers of units and due to the movable support for the heating, lighting or drying elements that the operator is afforded ready access to any part of the press for the purpose of setting it up for various maintenance purposes. In addition it will have been observed how easily the cylinders of one type can be removed and replaced with cylinders of a different type as desired.

Although preferred embodiments of the invention have been illustrated and described herein, it will be understood that the invention is susceptible of various modifications and adaptations within the scope of the appended claims.

Having thus described my invention I claim:

1. A printing press comprising a base provided with two sets of longitudinally extending parallel rails with the adjacent ends of the rails of said sets spaced apart longitudinally of the base, said base also being provided with transversely extending guide means located intermediate said sets of rails, groups of cooperating units supported by said base and operatively associated with said sets of rails, with the units of each group relatively movable longitudinally of the base with respect to each other to an operative position for printing purposes or to a separated non-operative position for setup or maintenance purposes, the cooperating units of each group being provided with printing elements wherefore printing couples are provided spaced apart longitudinally of said base and a web of print receiving material can be reeved through said couples to receive on opposite sides of the web printed images simultaneously produced by the couples, means for securing said cooperating units in said operative position, and means operatively and movably associated with said transversely extending guide means to be positioned intermediate said spaced printing couples in close proximity to both sides of said web for drying the printed images thereon or to be moved from between the couples to an inactive position when the web is being reeved through the couples.

2. A printing press comprising a base provided with longitudinally extending guide means, tiers of superimposed units supported by said base and operatively associated with said guide means and relatively movable therealong with respect to each other to an operative position for printing purposes or to a separated non-operative position for setup or maintenance purposes, said units being provided with printing elements and correlated units of the tiers constituting printing couples, means for securing said tiers in said operative position, a power shaft extending longitudinally of the base and parallel to said guide means, and operative connections between said shaft and the printing elements of the superimposed units of a plurality of said tiers, said operative connections being movable with said tiers and axially of said shaft.

3. In a printing press, a base, a plurality of relatively movable cooperating units mounted on said base and provided with printing elements and constituting a printing couple, said units being relatively adjustable to an operative position for printing purposes or to a spaced non-operative position for setup or maintenance purposes, said printing elements including means for creating an electro field of force and carried in part by one unit and in part by an adjacent unit, a motor generator set carried by one of the units with the motor thereof adapted to be connected to a source of electrical energy, and electrical conduit means interconnecting said set with said means for creating an electro field of force.

4. In a printing press, a base, a plurality of cooperating units movably supported on said base and provided with printing elements, said units being relatively adjustable to an operative position for printing purposes or to a spaced non-operative position for setup or maintenance purposes, one of said units being provided with a porous cylinder forming a printing element and with a tubular support for said cylinder coaxial with said cylinder and having an opening communicating with the exterior of said cylinder and another of said units being provided with a liquid reservoir, and flexible conduit means extending from said reservoir to said tubular support and interconnecting said reservoir of the one unit with the interior of said cylinder of the other unit in the various relatively adjusted positions of the units.

5. In a printing press, a base, a plurality of cooperating units movably carried by said base to be adjusted to an operative position for printing purposes or to a spaced non-operative position for setup or maintenance purposes, said units being provided with printing elements and constituting a printing couple, certain of said elements including means for creating an electro field of force and carried by adjacent units, certain of said elements including a porous cylinder, one of said units being provided with a motor generator set the motor of which is adapted to be connected to a source of electrical energy, said one unit also being provided with a reservoir for liquid, means electrically connecting said motor generator set with said means for creating an electro field of force, and conduit means interconnecting said reservoir with the interior of said porous cylinder.

6. In a printing press, a base, a plurality of relatively movable cooperating units mounted on said base and provided with printing elements and constituting a printing couple, said units

being relatively adjustable to an operative position for printing purposes or to a spaced non-operative position for set-up or maintenance purposes, said printing elements including means for creating an electro field of force and carried in part by one unit and in part by an adjacent unit, a motor generator set operatively associated with said press and having the motor thereof adapted to be connected to a source of electrical energy, and electrical conduit means interconnecting said set with said means for creating an electro field of force.

7. A printing press comprising a frame including base and upper frame members provided with longitudinally extending guide means, a plurality of supporting members on said base members and provided with means cooperating with the guide means of said base members, tiers of superimposed similar interchangeable units extending between said supporting members and said upper frame members, said units, said upper frame members and said supporting members being provided with cooperating portions interconnecting the units with each other and with said supporting members and the tiers with said guide means of the upper frame members for movement longitudinally thereof, cooperating means carried by said frame and said supporting members for moving said tiers toward and from each other to an operative position for printing purposes or to a separated non-operative position for set-up or maintenance purposes, said units being provided with printing elements and correlated units of said tiers constituting printing couples, and means cooperating with said frame and said supporting members for securing said tiers in said operative position.

8. A printing press as defined in claim 7 and wherein the uppermost units of said tiers and the upper frame members are provided with cooperating means operatively interconnected with the cooperating means of the frame and supporting members for moving the tiers longitudinally of the frame, and wherein means cooperating with said upper frame members and said uppermost units of said tiers function to secure said tiers in operative position.

9. A printing press comprising a frame including base and upper frame members provided with longitudinally extending guide means, tiers of superimposed similar and interchangeable units extending between said members, the units of each tier being provided with portions cooperating with the immediately adjacent units in the tier to detachably interconnect the units in the tier with each other to form the tier of units into a united structure, the cooperating portions of the uppermost and lowermost units in the tier being operatively associated with said guide means, wherefore the tier can move as a unit longitudinally of the frame and adjacent tiers can be moved relatively to each other to an operative position for printing purposes or to a separated non-operative position for set-up or maintenance purposes, said units being provided with printing elements and the units of one tier cooperating with the corresponding units of an adjacent tier to constitute printing couples, and means cooperating with said base and upper frame members for securing said tiers in said operative position.

10. A printing press comprising a frame including base and upper frame members provided with longitudinally extending guide means, groups of

cooperating tiers of superimposed and similar units extending between said base and upper frame members and supported and guided thereby, the units of each tier being provided with portions cooperating with the immediately adjacent units in the tier to detachably interconnect the units in the tier with each other to form the tier of units into a united structure, the cooperating portions of the uppermost and lowermost units in the tier being operatively associated with said guide means, wherefore the tier can move as a unit longitudinally of the frame and the cooperating tiers of each group can move relatively with respect to each other to an operative position for printing purposes or to a separated non-operative position for set-up or maintenance purposes, said groups of tiers being spaced apart longitudinally of the frame, correlated units of each group of tiers being provided with printing elements and the correlated units of each group constituting a plurality of superimposed printing couples adjustable toward and from each other, wherefore a continuous web of print receiving material can be reeved through the printing couples of all the groups and printed images reproduced simultaneously by the couples on both sides of said web, and means cooperating with said base and upper frame members for securing the tiers of each group in said operative position.

11. A printing press comprising a frame including a base provided with longitudinally extending guide means, tiers of superimposed similar and interchangeable units supported by said base, the units of each tier being provided with portions cooperating with the immediately adjacent units in the tier to detachably interconnect the units in the tier with each other to form the tier of units into a united structure, the cooperating portion of the lowermost unit in the tier being operatively associated with said guide means, wherefore the tier can move as a unit longitudinally of the frame and adjacent tiers can be moved relatively to each other to an operative position for printing purposes or to a separated non-operative position for set-up or maintenance purposes, said units being provided with printing elements and the units of one tier cooperating with the corresponding units of an adjacent tier to constitute printing couples, and means cooperating with said base for securing said tiers in said operative position.

WILLIAM C. HUEBNER.
